UNITED STATES PATENT OFFICE.

NEWTON C. OWEN, OF WILKES-BARRE, PENNSYLVANIA, ASSIGNOR TO OWEN-PENNSYLVANIA CORPORATION, OF WILKES-BARRE, PENNSYLVANIA, A CORPORATION OF PENNSYLVANIA.

RAILROAD-TIE-CHANGING MACHINE.

Application filed March 24, 1921. Serial No. 455,073.

To all whom it may concern:

Be it known that I, NEWTON C. OWEN, of Wilkes-Barre, county of Luzerne, and State of Pennsylvania, a citizen of the United States of America, have invented certain new and useful Improvements in Railroad-Tie-Changing Machines, of which the following is a specification.

Some of the objects of this invention are to provide an improved railroad track maintenance machine, whereby worn out railroad ties may be quickly and conveniently removed from operative position and replaced with a new tie; to provide a tie removing machine whereby a tie may be removed with minimum disturbance of the road bed and a new tie replaced with the minimum amount of tamping; to provide a tie removing machine which is quickly removable along the rails longitudinally and may be quickly removed from the rails to permit of the passage of traffic; to provide in a railroad track maintenance machine improved means for anchorage and to provide other improvements as will appear hereinafter.

In the accompanying drawings:

Figure 1 is a top plan view of a railroad track maintenance machine constructed in accordance with this invention; Fig. 2 a side elevation of the same; Fig. 3 an enlarged front elevation of a tie hook forming part of this invention; Fig. 4 a longitudinal section on the line 4-4 of Fig. 3; Fig. 5 an end elevation of the hook shown in Figs. 3 and 4; and Fig. 6 an enlarged fragmentary top plan view of details of this invention.

Referring to the drawings one embodiment of this invention is shown mounted upon the usual railroad rails 5, 5 which are supported upon the usual tie plates 6 mounted on railroad ties 7 imbedded in the usual ballast or road bed 8, the rails being secured in position by the usual rail spikes 9. This form of this invention comprises a rigid frame 10 which extends transversely of the rails and projects equally upon opposite sides of the rails a suitable distance beyond the rails. The frame 10, as shown in the drawings comprising two parallel channel beams 11, 12 held in fixed spaced relationship by means of I-beam spacers 13, 14 which are securely riveted or bolted to the channel beams 11 and 12. The frame 10 is removably supported upon the rails 5, 5 by

two pairs of flanged wheels 15, 16, 17, 18 which are rotatably mounted respectively upon two pairs of axles 20, 21, 22, 23. These four axles are fixedly secured respectively in four pairs of rigid brackets 25, 25, 26, 26, 27, 27, 28, 28, which are rigidly secured to the frame 10.

For supporting any suitable power transmission or power mechanism a rigid flat horizontal sheet metal platform 35 is centrally mounted upon and is rigidly secured to the frame 10 by rivets or bolts 36 or by any other suitable means. This platform may be oblong, and rectangular in shape or may be of any other form suitable for performing the desired function.

Mounted upon the platform 35 is any power device 40 suitable for performing the desired function, which in the present case is the removal of a tie. In the drawings there is shown for this purpose a power device 40 which in the main is of well known construction, and which includes a rigid frame 41 in which is rotatably arranged a vertical shaft 42 commonly known as the high speed plug, which is provided at its upper end with a square portion 43 adapted to receive a hand lever 44. This shaft 42 carries loosely mounted thereon a drum 45 and a ratchet wheel 46 rigid with the drum. The drum 45 is arranged to be rotated at a comparatively high rate of speed in a well known manner by the high speed plug 42 acting through an internal pawl or pawls and ratchet (not shown). The frame 41 also supports a vertical shaft 50 commonly known as the high power plug provided at its upper end with a square portion 51 also adapted to receive the hand crank or lever 44. The drum 45 may also be rotated in a well known manner at a comparatively slow rate by the shaft or high power plug 50 acting through the intermediary of a plurality of pawls (not shown) acting externally upon the ratchet wheel 46.

This power device 40 has been modified and improved for the purpose of this invention by the addition of a hook 55, designed for the purpose, which is either rigidly secured to or integral with the frame 41.

The power device 40 preferably rests loosely upon the platform 35, and, for the purpose of this invention, may or may not be provided with a downwardly extending

- king pin 56 rigid therewith which is arranged to engage loosely in an elongated aperture 57 provided therefor through the platform 35 and arranged longitudinally and centrally thereof. The king pin 56 is normally arranged centrally of the aperture 57 and is freely movably longitudinally of the aperture and is freely withdrawable vertically therefrom.
- 10 For the transmission of power from the power puller 40 to one of the ties 7 to remove the same from its ballast or bed 8, a cable 60 of braided wire or other suitable construction or material is terminally secured at one end and is wound around the drum 45 and passes from the drum over a vertical sheave or pulley 61, which is spaced centrally between the ends of the channel beams 11 and 12 of the frame 10. This pulley 61 is arranged centrally of and is fixedly secured to a horizontal shaft 62 which projects in the opposite direction therefrom and which is cylindrical in form and reduced in diameter at each end to provide cylindrical journals 63 which engage snugly but rotatably in two corresponding downwardly extending recesses 64, 65, providing bearings therefor in the ends of the two channel beams 11, 12 of the frame 10, a pair of these recesses being provided symmetrically at each end of the frame so that the pulley 61 with its shaft 62 and journals 63, may be optionally arranged at either end of the frame 10. To provide suitable areas of bearing surfaces for the journals 63, the inner sides of the opposite ends of the channel beams 11, 12 are preferably reinforced by two pairs of steel plates 66, 67, 68, 69 which are rigidly secured respectively to the corresponding channel beams by means of bolts or rivets 70 each of the plates being provided with a recess which registers with the corresponding recess 64, 65 of the channel beams. The cable 60 extends over the periphery of the sheave 61 and then passes under the rails 5, 6 between the rails and the upper surface of the ballast or bed and terminates in a suitable hook 71 which is rigidly secured to the cable 60 by any suitable means. The hook 71 is adapted to engage in and be removable from the eye of a rigid specially constructed tie hook 73 which is designed to engage the end of a tie 7 to force it longitudinally from its bed.
- 15 The tie hook 73 as shown in Figs. 3, 4 and 5 may be formed in a single steel casting comprising an approximately straight shank 75 and an approximately straight hooked portion 76 integral with the shank and forming therewith an internal angle 77 which is preferably slightly obtuse. The shank is substantially uniform in width throughout the major portion of its length from its outer end and then tapers in width towards
- 20 the hooked portion 76. The shank 75 tapers
- 25
- 30
- 35
- 40
- 45
- 50
- 55
- 60
- 65

in thickness from the hooked portion 76 outwardly, and is provided with an oblong rectangular eye 78, and at its other end with an internal recess 79 adapted to receive the outer end of the smaller hook 71. The hooked portion 76 is braced by two ribs 80, 81, forming extensions on the side walls of the shank 75, and is provided near its outer end with two spurs 82, 83, integral with or rigidly secured thereto to engage in the outer end of the tie to hold the hook securely in position. The spurs 82 and 83 may be omitted.

For anchoring the power puller 40 a chain 90, or other flexible securing means, is engaged at one end by the hook 55 and is provided at its other end with a rail hook 95 which is adapted to engage either on the ball 96 of a rail or under the base 97 of a rail. This chain 90 or flexible connection extends loosely over a cylindrical horizontal sleeve 98 which is fixedly clamped between the two channel beams 11, 12 by means of a bolt 99 extending through the channel beams and provided with a head 100 at one end and at the other end with a suitable nut 101, and a lock washer. This sleeve 99 and its bolt 98 are duplicated upon the opposite side of the frame 10 so as to permit the machine to be anchored from the right hand rail instead of the left hand rail, as shown, when the direction of operation of the machine is reversed, to draw the tie to the left instead of to the right, as in the drawings.

In the operation of this improved machine for changing ties, the machine may be set up, as shown in the drawings, directly over the particular tie it is desired to remove, the rail spikes and tie plates of that tie having first been removed. In passing the cable 60 beneath the rails, the tie hook 75 is first disconnected from the smaller hook 71, to facilitate the operation, and is replaced on the smaller hook after the smaller hook 71 with the cable 60 attached has been drawn beneath the rails. The hand crank or lever 44 is then reciprocated through a suitable arc, thus acting through the ratchet 46 to rotate the drum 45 to wind up the cable 60 upon the drum. This process is continued until the tie 7 has been entirely removed from beneath the rail.

For inserting a new tie in the place of the tie just removed the power puller 40 is suitably adjusted to permit the cable 60 to be quickly unwound. The free end of the cable is drawn through the recess left by the old tie until the free end of the cable comes opposite the outer end of a new tie whereupon the tie hook 73, which has been removed from the cable to facilitate the operation of the passing of the cable under the rail is again secured to the end of the cable and is arranged to engage the outer end of a new tie, whereupon the power puller 40

is again adjusted and the power is applied through the reciprocation of the hand lever 44 upon the high power plug 50 and the new tie is drawn under the rail and into the recess occupied by the old tie and in proper position upon the road bed with relation to the rails. During this operation of removing and replacing the tie it is generally unnecessary to remove the ballast or disturb the 10 road bed or use any apparatus or tools other than the improved remover above described. It has been found possible with this tie machine to remove a tie of given width and replace it with a tie of considerably greater 15 width without previously enlarging the recess made by the old tie.

When it is desired to reverse the operation of this improved tie puller the hook 95 is released from the rail 96 and the frame 41 20 of the power puller 40 is rotated through 180 degrees. The sheave 61 and its bearings are then transferred from the right hand side of the frame 10 to the left hand side of frame 10 with the journals of the sheave 25 loosely engaging in the corresponding bearings 65. The cable 60 is then placed in position over the sheave and the machine is thus adjusted to draw a tie towards the left as viewed in the drawings. This adjustment of the machine to move a tie either in one direction or another is made 30 by the operator to meet local conditions.

It is to be understood that this invention is not limited to the specific construction 35 shown in the drawings and as heretofore described, as many changes might be made in the details of construction to adapt the invention to various purposes. For instance, instead of the hand power device 40, any 40 other well known or suitable hand pulling device might be used, or any other suitable means for providing the necessary power, such as a drum rotated by a gasoline engine, an electric motor, a steam engine, or any 45 other form of power device for supplying power to the cable 60 might be substituted for the device 40 shown.

It is also to be understood that instead of anchoring the power device 40 to only one 50 of the rails, as shown in the drawings, it might be advantageous in some cases to anchor to both rails at the same time. For instance, instead of having the power device 40 loosely mounted upon the platform 55 35 and anchored to one rail by the chain 90 and hook 95, the power device 40 might be fixedly secured to the platform 35 and in that case the frame with its platform might be anchored with one or more chains or 60 hooks or other similar devices to either one or both of the rails, and the power device 40 might in this case be arranged so that it could be detachably rotatable to 180 degrees more or less as might be found desirable, for 65 changing the direction of action of the power

device without disturbing the anchoring means.

These and various other changes and modifications might be made in this improved machine without departing from the 70 spirit of the invention or the scope of the appended claims.

Having thus described my invention, what I claim and desire to secure by Letters Patent is:—

75

1. A device for removing railroad ties including supporting means adapted to be mounted upon the rails of a railroad and means including power transmission means carried by said first mentioned means for removing a tie from beneath said rail, said power transmission means having a self-adjusting mounting on the supporting means.

80

2. A device for removing railroad ties including means adapted to be mounted upon the rails of a railroad, and means including power transmission means for removing a tie from beneath said rails, and means for directly anchoring said power transmission means to one of said rails.

85

3. In a repair device for railroads, the combination with a support adapted to be mounted upon the rails of a railroad, of power transmission means carried by said support and freely movable transversely of said rails with respect to said support and means actuated by said power transmission means for removing a tie from beneath said rails.

90

4. In a repair device for railroads, the combination with a support arranged to be mounted upon the rails of a railroad, of power transmission means carried by said support and anchorage means directly connected with said power transmission means 100 and arranged to engage one of said rails to hold said power transmission means against movement.

100

5. In a repair device for railroads, the combination with a support arranged to be 110 mounted upon the rails of a railroad, of power transmission means carried by said support and freely movable with respect thereto, and anchorage means arranged to engage one of said rails to hold said power 115 transmission means against movement.

110

6. In a repair device for railroads, the combination with a support arranged to be mounted upon the rails of a railroad, of a power device carried by said support, anchorage means arranged to anchor said power device to one of said rails, a rotary element carried by said support with its lowest portion approximately in a plane with the lower surfaces of the rails, a flexible 120 transmission means arranged to extend over said rotary element and to be actuated by said power device for removing a tie from said railroad.

125

7. In a repair device for railroads, the 130

- combination with a support arranged to be mounted upon the rails of a railroad, of a power device carried by said support, anchorage means arranged to anchor said power device to one of said rails, a rotary element carried by said support, a flexible transmission means arranged to extend over said rotary element and to be actuated by said power device for removing a tie from said railroad, said rotary element being arranged to be operatively positioned upon said support selectively upon either side of said rails.
8. In a repair device for railroads, the combination with a support arranged to be mounted upon the rails of a railroad, of power transmission means carried by said support and adjustable to apply force either in one direction or in a substantially opposite direction with respect to said support, a rotary element carried by said support and selectively adjustable with respect to said support upon either one side or the opposite side of said rails and a flexible connector arranged to be actuated by said transmission means and adjustable to be actuated over said rotary element for removing a tie from beneath said rails.
9. In a repair device for railroads, the combination with a support arranged to be mounted upon the rails of a railroad, of power transmission means carried by said support and rotatably adjustable to apply force either in one direction or in a substantially opposite direction with respect to said support, a rotary element carried by said support and selectively adjustable with respect to said support upon either one side or the opposite side of said rails and a flexible connector arranged to be actuated by said transmission means and adjustable to be actuated over said rotary element for removing a tie from beneath said rails.
10. In a repair device for railroads, the combination with a support adapted to be mounted upon the rails of a railroad and to project in opposite directions therefrom beyond the extremities of the ties of the road, two pairs of spaced bearings provided on said support beyond the opposite ends of said ties respectively, a rotary element provided with spaced journals adjustable either in said bearings upon one side of said extremities or in said bearings upon the other side of said extremities and power transmission means carried by said support and including a flexible connector adjustable to extend over said rotary element.
11. In a repair device for railroads, the combination with a support adapted to be mounted upon the rails of a railroad and to project in opposite directions therefrom beyond the extremities of the ties of the road, of two pairs of spaced bearings provided on said support beyond the opposite ends of
- said ties respectively, a rotary element provided with spaced journals adjustable either in said bearings upon one side of said extremities, or in said bearings upon the other side of said extremities, power transmission means carried by said support and including a flexible connector adjustable to extend over said rotary element, and means arranged to engage one of the rails of said road for holding said support against movement with respect to said rails.
12. In a repair device for railroads, the combination with a support adapted to be mounted upon the rails of a railroad, of a power device supported thereon and adjustable transversely of the rails, an anchoring connection extending from said power device and engageable with one of the rails to provide an anchorage for said power device and to locate the same transversely of the support and a power transmission connection extending from the thus anchored power device.
13. The device of claim 12 in which the anchorage and power transmission connections are both tension elements extending in opposite directions from the power device.
14. The device of claim 12 in which the support has a rigid extension at one side projecting beyond the rail and carrying a sheave disposed with its lower peripheral portion approximately in the plane of the lower surface of the rail and in which the power transmission connection is a flexible tension element extending from the power device over said sheave.
15. The structure of claim 14 in which a tie hook is detachably engaged with the power transmission connection.
16. The device of claim 12 in which the support is a rigid beam structure on top of which the power device is slidingly mounted.
17. In a repair device for railroads, the combination with a support adapted to be mounted upon the rails of a railroad and to project in opposite directions from said rails and beyond the ends of the usual ties upon which said rails rest, said support being provided at its opposite ends respectively with two pairs of spaced bearings, a sheave provided with spaced journals rigid therewith and arranged to be mounted either in said bearings at one end of said support or in said bearings at the other end of said support, a power device carried by said support, a flexible connector arranged to be actuated by said power device and adjustable to extend over said sheave in either of its positions and beneath said rails, and means operatively connected to said power device and adjustable to engage one of said rails to anchor said power device against movement in one direction.
18. In a repair device for railroads, the combination with a support adapted to be

- mounted transversely upon the rails of a railroad and to project in opposite directions from said rails beyond the ends of the usual ties upon which said rails rest, said support being provided at its opposite ends respectively with two pairs of spaced bearings, a sheave provided with spaced journals rigid therewith and arranged to be mounted either in said bearings at one end of said support or in said bearings at the other end of said support, a power device carried by said support and freely movable transversely of said rails with respect to said support, a flexible connector arranged to be actuated by said power device and adjustable to extend over said sheave in either of its positions and beneath said rails, and means operatively connected to said power device and adjustable to engage one of said rails to anchor said power device against movement in one direction with respect to said support.
19. In a repair device for railroads, the combination with a support adapted to be mounted transversely upon the rails of a railroad and to project in opposite directions from said rails beyond the ends of the usual ties upon which said rails rest, said support being provided at its opposite ends respectively with two pairs of spaced bearings, a sheave provided with spaced journals rigid therewith and arranged to be mounted either in said bearings at one end of said support or in said bearings at the other end of said support a power device carried by said support and freely movable transversely of said rails with respect to said support, a flexible connector arranged to be actuated by said power device and adjustable to extend over said sheave in either of its positions and beneath said rails, and means operatively connected to said power device and adjustable to engage one of said rails to anchor said power device against movement in one direction with respect to said support, said power device being adjustable to exert a pull upon said flexible connector either in one direction or in a substantially opposite direction.
20. A repair device for railroads comprising a support adapted to be placed over the rails of a railroad and having a portion extending laterally beyond said rails, flanged wheels rotatably mounted upon said support and adapted to engage said rails to carry said support longitudinally of said rails, a power device adjustably carried by said support, a rotary element carried by said laterally extending portion and arranged to rotate with respect thereto about an axis extending longitudinally of said rails, a flexible connector arranged to be actuated by said power device and extending over said rotary element and beneath said rails, a tie hook carried by said connector, and means directly connected to said power device and

arranged to engage a rail of said road to anchor said power device.

21. A repair device for railroads comprising a support adapted to be mounted upon the rails of a railroad and having a portion extending laterally and beyond said rails, a rotary element carried by said laterally projecting portion and arranged to rotate about an axis extending longitudinally of said rails, the lowest portion of said rotary element being approximately in a plane with the lower surfaces of said rails, a power device carried by said support, and a flexible transmission means actuated by said power device and extending over said rotary element.

22. A tie remover for railroads comprising a power device, a flexible connector actuated by said device and a tie hook secured to said connector, said tie hook comprising a shank, and a portion projecting from said shank and forming a slightly obtuse angle therewith, said portion being provided with means adapted to penetrate the end of a tie to hold the hook in position.

23. A tie hook comprising a shank and a portion projecting from said shank and forming a slightly obtuse angle therewith, said portion being provided with means adapted to penetrate the end of a tie to hold the hook in position.

24. A device for railroads comprising a support arranged to be mounted upon the rails of a railroad, a power device carried by said support, a rotary element carried by said support, a flexible connector extending from said power device over said rotary element and arranged to be actuated by said power device, an anchorage means operatively connected with said power device and arranged to engage one of said rails to hold said power device against movement transversely of said rails, said rotary element and said flexible connector and said anchorage means being arranged substantially in a vertical plane which is approximately perpendicular to said rails.

25. A device for railroads comprising a support arranged to be mounted upon the rails of a railroad, a power device carried by said support, a rotary element carried by said support, a flexible connector extending from said power device over said rotary element and arranged to be actuated by said power device, anchorage means operatively connected with said power device and arranged to engage one of said rails to hold said power device against movement transversely of said rails, said rotary element and said flexible connector and said anchorage means being arranged substantially in a vertical plane which is approximately perpendicular to said rails and said power device being normally freely movable transversely of said rails.

26. A device for railroads comprising a

- support arranged to be mounted upon the rails of a railroad, a power-device carried by said support, a rotary element carried by said support, a flexible connector extending from said power device over said rotary element and arranged to be actuated by said power device, and anchorage means operatively connected with said power device and arranged to engage one of said rails to hold said power device against movement transversely of said rails, said rotary element and said flexible connector and said anchorage means being arranged substantially in a vertical plane which is approximately perpendicular to said rails and said power device being normally freely movable transversely of said rails but being held against movement with respect to said support longitudinally of said rails.
27. In a device for railroads, the combination with a support, comprising two oppositely disposed beams held in fixed spaced relationship, of a platform superimposed upon said beams, a power device mounted upon said platform, a rotary element extending between said beams and arranged to rotate about an axis fixed with respect thereto and extending transversely thereof, a flexible power transmission means adjustable to extend from said power device over said rotary element, and anchorage means adjustable to extend from said power device between said beams to engage one of said rails to hold said power device against movement in the direction of said rotary element.
28. In a device for railroads, the combination with a support comprising two oppositely disposed beams held in fixed spaced relationship, a platform superimposed upon said beams, a power device mounted upon said platform and freely movable with respect thereto, a rotary element extending between said beams and arranged to rotate about an axis fixed with respect thereto and extending transversely thereof, a flexible power transmission means adjustable to extend from said power device over said rotary element, and anchorage means adjustable to extend from said power device between said beams to engage one of said rails to hold said power device against movement in the direction of said rotary element.
29. A repair device for railroads, comprising a support including oppositely disposed, parallel beams arranged in substantially the same horizontal plane and held in fixed spaced relationship, a platform superimposed upon and rigidly secured to said beams and provided with an oblong opening arranged between said beams and extending in a direction substantially parallel thereto, a power device mounted upon said platform and provided with a king pin extending loosely in said opening and movable

longitudinally thereof, a flexible connector operatively connected to said power device at a point approximately in a vertical plane substantially parallel to and extending between said beams, said flexible connector being provided with a hook arranged to engage a rail of a railroad to hold said power device against movement in one direction longitudinally of said beams, a rotary element extending between said beams and provided with a pair of oppositely disposed journals arranged to engage in bearings provided therefor on said beams respectively, and a flexible transmission means arranged to extend from said power device over said rotary element.

30. In a repair device for railroads, the combination with a support adapted to be mounted upon the rails of a railroad, of a power device carried by said support, a flexible anchorage connection extending from said power device toward one of the rails and provided with means for securing the same to said rail and a flexible pulling connection extending from the power device in the opposite direction toward the other rail.

31. In a repair device for railroad ties, the combination of a support adapted to be mounted upon the rails of a railroad, of power transmission means carried by said support and freely movable transversely of said rails with respect to said support, and means actuated by said power transmission means for removing and replacing a tie of said railroad.

32. In a device for railroads, the combination with a support comprising two oppositely disposed beams held in fixed spaced relationship, of a power device supported upon said beams, a rotary element journaled on the beams, a flexible power transmission connection extending from the power device over said rotary element and adjustable anchorage means extending from the power device and provided with means for securing the same to one of the rails of a railroad.

33. A repair device for railroads, comprising a support adapted to be mounted upon the rails of a railroad and having a portion extending laterally beyond the rails, a rotary element carried by said laterally extending portion of the support and arranged to rotate about an axis disposed longitudinally of the rails with the lowest portion of said rotary element turning approximately in a plane with the lower surfaces of the rails, a power device mounted on the support, flexible transmission means actuated by said power device and extending over the rotary element and connecting means from the power device to one of the rails.

34. A repair device for railroads, comprising a support adapted to be mounted

upon the rails of a railroad and having a portion extended laterally beyond the rails, a rotary element carried by said laterally extending portion of the support and arranged to rotate about an axis disposed longitudinally of the rails with the lowest portion of said rotary element turning approximately in a plane with the lower surfaces of the rails, a power device mounted on the support, flexible transmission means actuated by said power device and extending

over the rotary element and means for enabling reversal of the pulling effect of the power device and flexible power transmission means.

15

35. The structure of claim 33 with a tie hook engaged by the flexible transmission means, said tie hook having a self-adjusting holding engagement with the ties.

In testimony whereof I hereunto affix my signature.

NEWTON C. OWEN.
